CONTAINER CAPPING MACHINE

John J. Gaynor, Delphi, Ind., assignor of one-half to Arthur I. Risser, Chicago, Ill.

Application August 8, 1933, Serial No. 684,236

19 Claims. (Cl. 226—84)

This invention relates to container capping machines, and more particularly pertains to bottle crowners as employed in association with container or bottle filling machines.

5 The type of filling machine in connection with which the capping machine of the invention is of especial utility, is that having means for constantly conveying containers in uniform single order in close arrangement, and wherein the machine has means for filling said containers as they are being conveyed, and wherein both the filling and capping machines are adapted to be driven by power means common to both. One object of the invention is to provide such a capping machine with two alternately operated capping heads and means for transferring containers from the conveying means of the filling machine and placing them alternately into cooperative relation with the capping heads to be 10 alternately capped thereby, and having operating mechanism so arranged for balanced action that enables an increased output of the machines without transmitting any jarring or vibratory action to the filling machine by the intermittent 15 capping of the containers.

Another object of the invention is to provide such a machine as outlined which enables close uniformity of caps as applied to the bottles capped by the separate heads.

20 Although the capping machine is of especial utility in connection with filling machines as stated, the invention is not to be so limited because the balanced action of the machine is of advantage in the machine itself in expediting the capping of containers and in prolonging the effectiveness of the machine.

Other objects and advantages will become apparent by reference to the specification, claims and the accompanying drawings, in which:

25 Fig. 1 is a small diagrammatic view illustrating the capping machine of the invention as applied to a common type of container filling machine of the rotary class, and as looking toward the side of the capping machine.

30 Fig. 2 is a front view of the capping machine showing a portion of the filling machine, with parts broken away, and the view being of larger scale than Fig. 1.

Fig. 3 is a vertical section of the machine, the 35 view being taken substantially on the section line 3—3 of Fig. 2.

Fig. 4 is a vertical section taken substantially on the section line 4—4 of Fig. 2.

Fig. 5 is a plan section of a portion of Fig. 3, 40 the view being taken substantially on the sec-

tion line 5—5 of said figure and arranged at right angle to the position it would occupy as indicated by the section line.

Fig. 6 is a section of a portion of the mechanism shown in Fig. 2 as indicated by the section line 6—6 of said figure.

Fig. 7 is a plan section taken substantially on the section line 7—7 of Fig. 2, the view being of larger scale than Fig. 2.

Fig. 8 is an enlarged plan section of Fig. 2, 45 and taken substantially on the section line 8—8 of said figure.

Fig. 9 is an enlarged plan section of Fig. 2, taken on the section line 9—9 of said figure, and showing a portion of the filling machine. 50

Fig. 10 is an enlarged view of a portion of the mechanism shown in Fig. 7 with parts in changed position and parts being broken away.

Fig. 11 is a section taken on the section line 11—11 of Fig. 10. 55

Fig. 12 is a vertical section of one of the capping heads, the view being taken substantially on the section line 12—12 of Fig. 2, with parts omitted and parts broken away.

Fig. 13 is a vertical section taken substantially 60 on the irregular section line 13—13 of the Fig. 12 with certain parts omitted.

Fig. 14 is a view similar to Fig. 13 with parts in changed position and other parts shown in section with added parts. 65

Fig. 15 is a plan view of a portion of the parts shown in Fig. 13.

Fig. 16 is an enlarged view of a portion of Fig. 5, and also comprising a plan section of Fig. 12, but arranged at right angle thereto, and as taken 70 substantially on the section line 16—16 of Fig. 12.

Referring to Fig. 1, the filling machine "A", somewhat diagrammatically illustrated, is of the well known type, in the rotary class. The machine comprises a circular filling tank 2 mounted 75 on a central pedestal support 3 rotatably mounted in a suitable manner concentric with the tank, on the base support 4. Arranged equally spaced about the axis of the tank and depending from the edge thereof, are vertically reciprocable filling heads 5 which are adapted to dispense liquid from the tank upon being raised therein.

The filling machine has means for conveying containers or bottles under the filling heads in cooperative relation therewith. Said conveying means includes a plurality of vertically disposed hollow plungers 6 equally spaced about the pedestal axis so that each plunger is below a filling head and central therewith. The plungers 6 are reciprocably mounted in bearings 7 in 100 105

110

the periphery of the circular lateral extension 8 of the pedestal 3. Removably secured at the top end of each plunger, is a stirrup 9 having an outwardly open yoke 10 for receiving the containers 5 or bottles 11 to be filled, and in which the bottles are positioned under the filling heads central therewith.

The filling machine rotates continuously in clockwise direction as viewed in plan, and as the plungers cross the station as indicated by the vertical dot and dash line B—B in Fig. 2, the bottles are placed in the stirrups by automatic means, not shown, and at which point the plungers are in lowered position. The plungers are then moved to raised position, causing the bottles to enter and raise the filling heads, in which position they remain during considerable movement of the machine to effect the filling of the bottles. The filled bottles are then lowered by the plungers before reaching the bottle receiving station, and are then transferred to the capping machine embodying the invention. It may be mentioned that the plungers are operated by a circular cam track 12 on the base support, which is engaged by rollers 14 on the levers 15 radiating from the pedestal on which they are pivotally connected, and whose other ends are pivotally connected through the intermediation of the connecting rods 16 to the plungers.

30 After the plungers 6 reach their lowered position, the filled bottles thereon are transferred or deflected sharply outward radially of the filling machine between the spaced curved ends 20 and 21 of spaced bottle guide rails 22 and 23, and onto a container support 24 in the form of a table whose top surface is in the plane of the bottoms of the stirrups. Upon being placed on the table, the bottles are engaged by a horizontally disposed oscillating arm 25 which deflects 35 the bottles in opposite directions alternately to position same at locations indicated by the crosses C and D on opposite sides of the axis of oscillation of the bottle positioning arm, as shown in Fig. 9. The station at which the bottles are initially placed on the table is directly between the axes of the filling machine and the bottle positioning arm, as indicated by the dot and dash line E—E on Fig. 9. For cooperating with the arm 25 in positioning the bottles at said locations, the guide rails 22 and 23 are oppositely arcuately formed about the axis of oscillation of the arm, as at 26 and 27 respectively, and which portions extend from their respective curved ends 20 and 21, inward toward the axis of oscillation of the arm. The arm has a small hub portion 28 which is suitably mounted on the top end of a vertical shaft 29, rotatably mounted in a bearing 30 in the table. The arm hub portion has spaced end flange portions 31 from which extend spaced parallel reduced upper and lower arm portions 32 to form the bottle positioning pockets 33 and 34 on opposite sides of the arm for positively locating the bottles at either of the capping locations C and D, at the limits of movement of the arm, in one position of which the arm is shown in dot and dash lines in Fig. 9.

Spaced above the table and on opposite sides of the axis of the arm shaft, are two capping heads 35 and 36 arranged to be in cooperative relation respectively with the pockets 33 and 34 of the arm, when same is at either of its limits of oscillation, for capping the bottles alternately positioned by the arm.

As succeeding bottles to be capped are positioned for capping, the capped bottles are ejected

from under their respective capping heads by being engaged by the ends of outwardly sprung pawls 37 and 38 which extend from opposite sides of the arm. On the return stroke of the arm from either of its limits of movement, the pawls are caused to recede by riding over the positioned bottles. The purpose of the pawls is to prevent the bottles from bumping which greatly eliminates breakage. The pawls have spaced bearing portions 39 which are hinged to a vertical pin 40 at the end of the arm 25 and extending between its arm portions. A coil spring 41 surrounds the pin with its ends connected to opposed bearings of the pawls for resiliently urging the pawls outward to positions determined by a projection 42 on one of the bearings of each pawl engaging the end portion 43 of the arm which joins the arm portions.

As the bottles are ejected they are directed in separate rows on the table, which are formed by the parallel end portions 44 and 45 of the guide rails 22 and 23 respectively, and between which end portions extends a partition 46 mounted on the table. The bottles capped may be taken from the table by hand or the upper stretch of a conveyor belt may be positioned alongside the table to convey the bottles therefrom. 95 100

The table is mounted on two vertically positioned uprights 47 and 48 in the form of shafting or rods which are secured at their bottom ends to 105 a pedestal 49 which is mounted on the base of the filling machine, and the top ends of the uprights are connected by the brace 50.

The shaft 29 on which the bottle positioning arm is mounted, is rotatably mounted at its lower end in a bearing 51 on the top of the pedestal 49, and which shaft is in operable connection with the filling machine for oscillating the arm in timed relation therewith. To this end the shaft 29 has a crank arm 52, releasably secured thereto in a manner later described, which arm is pivotally connected at its free end to a connecting link 53, whose other end is pivotally connected to a crank 54 mounted on the lower end of a power shaft 55 extending upward through and in key connection with the hub portion 56 of a spur gear 57, which hub portion is rotatably mounted in a bearing 58 in the table. Meshing with the gear 57 is a spur gear 59 in slidable key connection with a vertical shaft 60 rotatably mounted in a bearing 61 in the table top, the gear being held positioned between the bottom end of the bearing and a support plate 62 suitably mounted on the table, and through which the shaft extends. Meshing with the gear 59 is a spur gear 63 rotatably mounted on a stub shaft 64 depending from the table. Rotatably mounted on the stub shaft and connected with the gear 63 is another smaller spur gear 65 which meshes with a ring spur gear 66 mounted on the periphery of the lateral circular extension of the filling machine, which ring gear serves as a connection with gear driving means, not shown. The gears, crank arms and bottle positioning arm are so proportioned and timed, that as the bottles are transferred onto the table, they are carried to their positions or locations to be capped alternately. The crank arm 52 is releasably connected on the shaft 29 by means of an arm extension 67 of the crank on which is mounted a spring pressed pin 68 whose inner end is conically formed to engage in the conical recess 69 in the side of a collar 70 secured to the shaft, said crank arm being loose on the shaft and held between said collar and a collar 71 on the shaft. Thus in the event a bottle 150

becomes jammed between the positioning arm and the guide rails, the spring pressed pin is disengaged from the collar 70, whereby the crank arm becomes loose on the shaft, to prevent 5 breaking the bottle.

The capping heads 35 and 36 mentioned briefly in the foregoing will now be described. Each capping head comprises a hollow cylindrical plunger 72, vertically disposed above the table, both plungers being positioned on opposite sides of the center line of the shaft 29 and arranged to be coaxial with the bottles positioned on the table. Each plunger extends through and is reciprocably mounted in a bearing bore 73 in the horizontal 10 elongated support 74 secured at its ends to the lower ends of two sleeves 75 and 76 which are respectively mounted for adjustment on the uprights 47 and 48. Across the top end of each plunger is a strike plate 77 which has a plug 15 formation 78 threaded into the end of the plunger. Extending upward from the support 74 and alongside of each plunger 72, is a guide bar 79 engaged on its side by the straight edge portion 80 of the strike plate on the plunger for preventing 20 the plunger from turning in its bearing, the guide bars being arranged in spaced relation between the plungers.

Near the bottom end of each plunger is a cap 25 receiving recess 81 for positioning a cap 82, of the well known bottle stopper type, central with the axis of the plunger with its open side facing 30 downward. The recess of each plunger has an inlet opening 83 extending forward of the machine in converging direction relation with the recess of the other plunger. Each plunger is so 35 operated that upon the positioning of a bottle thereunder, it is held in raised position with its recess opening in register or cooperative relation with a cap directing element 84 in the form of a 40 gravity feed cap magazine, being oscillatably mounted and containing a supply of crowns in uniform single order, and whose discharge end 45 is in register with said opening for feeding a cap or crown therein.

Upon the return movement of the bottle positioning arm after having positioned a bottle on the table, the capping head plunger over the bottle has been initially lowered over the bottle, the neck of the bottle entering the plunger 50 through its outwardly flared bottom opening 86 and engaging the cap so that the peripheral bead 87 about the bottle mouth is surrounded by the flared inwardly beaded skirt 88 of the cap. As the plunger is lowered further, the cap skirt becomes 55 engaged within the conical bore portion 89 of the constricting ring or collar 90 secured in the plunger above the recess and which effects the constriction of the cap skirt about the bead at the end of the bottle neck as the plunger is resiliently forced downward by means later described. As the cap is about to enter the constricting ring, it engages a spring pressed plunger head 91 slidably mounted in the ring which holds 60 the cap square with the bottle mouth, and which also effects ejection of the bottle from the capping head plunger. The ejecting plunger head has a stem 92 extending upward into a bearing in the plug portion of the strike plate, and a coil compression spring 93 surrounds the stem and is interposed between the plug portion and the plunger head which is thereby normally resiliently held in lowered position, with its bottom 65 end forming the top wall of the cap recess, by the annular shoulder 94 of the head engaging the top 70 of the constricting ring.

The cap magazine is in the form of a closed-sided chute with the crowns guided therein in edgewise uniform single order, and the chute being arcuately formed with a top end vertical portion 95, at which end it is pivotally mounted for horizontal oscillatable movement, as at 96, to the bottom discharge end 97 of a cap feeding device 98 mounted on the horizontal support 99 whose ends are mounted on the top ends of the sleeves 75, 76, and which support is arranged spaced above the support 74. The chute extends arcuately downward and inward to terminate in the horizontal discharge end portion 85 which is maintained in the plane of the recesses of the capping heads when same are in raised position, and which end is received, to be guided, in an arcuate groove 100 in the support 74, and which groove is concentric with the pivotal connection of the chute. The groove is intersected at its bottom arcuate wall 101 by the bearing bores of the capping head plungers to form openings 102 in the groove which register with the openings of the recesses of the plungers respectively, when the plungers are in raised position.

The magazine is continuously oscillated so that 100 its discharge end is alternately brought into register with the openings in the groove 100 when the capping head plungers are held in raised position with their recesses in register with said openings. At the discharge end of the magazine 105 are formed side wall extensions 103 which are permitted close registration with the openings in the groove in effectively guiding a cap into one of the recesses, because, as the magazine is returned from positioning a cap, the extension 103 of the 110 trailing side passes through the opening of the recess in which the cap has been positioned. The bottom wall 101 of the groove also serves to hold the caps in the magazine when same is out of cooperative relation with the capping heads. 115

It will be understood, by reference to Figs. 2 and 3, that at the neutral position of the magazine, its inlet end is in register with the discharge end 97 of the cap feeding device.

The feeding device has a horizontal centrally 120 located operating shaft 104 which is in driven connection with the vertical shaft 60 which extends upward from the table and through a bearing 105 in the lower support 74, to be received rotatable in a bearing 106 extending through the 125 upper support 99. The top end of the shaft 60 is suitably connected with the shaft 104 to drive same through the intermediation of gearing 107 and the sprocket chain and gear mechanism 108.

Means for operating the capping heads and the 130 magazine will now be described. Extending cross-wise over the lower support 74 in spaced relation are two similar stub shafts 109 and 110 respectively mounted in spaced bearings 111—111 and 112—112 on the support, and between which 135 shafts, the capping head plungers are positioned and arranged so that when in raised position, the tops of the striking plates are slightly below the horizontal plane of the shafts. Mounted respectively on the shafts 109 and 110 are similar operating levers 113 and 114 which extend inward in normal parallel relation on opposite sides of the capping heads, and which levers are respectively intermittently connected with the capping head plungers of the heads 35 and 36, during alternate oscillation of the levers, whereby the heads are intermittently reciprocated. To this end, each lever has a pin 115, extending horizontal, on which is mounted a roller 116 which, upon oscillation of its lever downward, is 140

caused to engage the strike plate of its respective plunger to lower same over a bottle. The plungers are each held in raised position by a locking device including a pawl 117 which is 5 pivotally mounted on a horizontal pin 118 extending through the strike plate and the slot 119 therein in which the pawl is confined for movement in a vertical plane, and which pawl normally projects upward into a hook formation 120 10 which is spring pressed into engagement with the top end of the guide bar adjacent the plunger, said end comprising the stop 121. For urging the pawl into engagement with the stop, the pawl has a lateral right-angular extension 122 15 received in the recess 123 in the top of the strike plate. The recess is bored out as at 124 to receive a compression spring 125 whose top end engages the under side of the pawl extension in resiliently holding the pawl engaged with the 20 step and with its extension slightly extended over the strike plate. Thus, as an operating lever is lowered to engage its respective plunger, its roller first engages the extension of the pawl thereof and rocks same out of engagement with the stop, 25 whereupon the plunger is free to be moved downward upon continued movement of the lever. To positively operably connect the plunger with the lever, so that it will be raised by the lever, the pawl has a hook formation 126 on its side opposite the hook 120, and which, when moved toward the roller on the release of the pawl, engages over a projection 127 extending from the enlarged end 128 of the roller pin of the lever. During reciprocation of a plunger, the pawl thereof is held released from the guide bar by the hook formation 126 being engaged on its end 129 30 by the bar, as best seen in Fig. 14. Thus as a lever reaches about its neutral position on its upward stroke, the pawl again becomes engaged with the stop and the hook formation 126 of the pawl becomes disengaged from the projection 127 of the roller pin end. By reason of the construction just described, the continuously oscillating operating levers effect the positive intermittent 35 reciprocation of their respective plungers in alternation.

Extending upward from hub portions 130 and 131 of the levers 113 and 114 respectively, are arm extensions 132 and 133 respectively arranged at substantially right angles to said levers, and whose top ends are pivotally connected as at 134-134, to a horizontal link 135 which maintains the arm extensions in parallelism so that the levers may oscillate alternately.

For resiliently operating the levers, the power shaft 55 has an upward extension 136 adjustably connected therewith just above the table for axial and angular adjustment, by a coupling device 137. Said shaft extension passes through a bearing 133 in the lower support 74 and is rotatably mounted in a bearing 139 of a bracket 149 mounted on the sleeve 76 on the upright 48, and at the top end of the shaft above the bracket is a driving element 141, in the form of a crank arm, whose free end is in pivotal connection, by means of the crank pin 142 thereon, to which is fulcrumed the loosely pivoted block member 143 of the yoke 144 of the universal coupling 145, to one end of a resilient link element 146 whose 60 other end is in connection with the yoke member 147 of the universal coupling 148 connecting the extending forked end 149 of the link 135.

The crank arm 141 also serves to oscillate the magazine, wherein the crank pin of the arm is 75 pivotally connected to one end of a link 150

whose other end is pivotally connected to the top end of a rocker arm 151, as at 152, and which arm is centrally pivoted, as on the pin 153, to the bracket 140. The lower end of the rocker arm is pivotally connected, as at 154, to one end of a link 155 whose other end is in pivotal connection to the top of the bottom portion of the magazine, as at 156. The crank arms of the power shaft and its extension are so angularly arranged that slightly prior to the return movement of the bottle positioning arm, after having positioned a bottle, as seen in Fig. 9, in which position the arm is shown in dotted lines, the capping head over the bottle is lowered to cap same, at which time the other capping head is held stationary in raised position with the magazine in position with its discharge end in register with the cap recess of said head, whereby a cap is supplied thereto, as seen in Fig. 2. 80 85 90 95 100 105 110 115 120 125 130 135 140 145 150 155 160 165 170 175 180 185 190 195 200

It will be seen that the operating levers and their arm extensions counter-balance each other during their operation, and the fact that each capping head plunger is positively raised by its operating lever, thus adding its weight to the lever instead of being raised by spring means, maintains substantially an even load on the power shaft with the intermittent load put on the shaft by the intermittent capping of the bottles. By the capping mechanism being so balanced, no jarring action is transmitted to the filling machine by the capping of the bottles, which would otherwise cause the dispositioning of the bottles on the conveying means of the filling machine with respect to the filling heads prior to the insertion of the bottles in the heads. This enables speeding up the operation of both the filling and capping machines without subjecting either machine to any great amount of wear to their mechanisms, and which also enables an increased output of both machines.

Referring to Figs. 2, 7, 10 and 11, the resilient link 146 includes respectively inner and outer tubular telescoping sections 157 and 158, having limited slidable movement with respect to each other by means of two opposed pins 159-159 mounted in the outer tube section and which pins pass through elongated slots 160-160, respectively, in the inner tube section. Threaded into the outer end of the inner tube is a threaded collar 161 through which is slidable a rod 162 which extends into the tube to normally engage at its free end with the plug 163 secured in the inner end of the tube. The outer end of the rod is in threaded connection with the yoke member 147 of the coupling 148 and locked thereto by the nut 164 on the rod. In the outer end of the outer tube is a plug 165 secured thereto, which plug has a threaded extension 166 in threaded connection with the yoke member 144 of the universal coupling 145, and locked thereto by means of the nut 167. Disposed in the inner tube is a compression spring 168 which surrounds the rod, with one end engaging the collar and the other end engaging the pins 159-159 which project into the inner tube. At the inner end of the rod are two opposed pins 169-169 which are also engaged by the end of the spring which engages the pins 159-159. Thus the tube sections are resiliently held in extended relation, in which position they are urged by the spring under stress, and likewise the inner tube section and the rod are held in retracted relation.

The resilient link is so arranged that when the operating crank arm 141 is in dead center relation with the link and extending away therefrom in 150

causing the operation of the capping head 36, as seen in Fig. 2, and Fig. 7, the pressure exerted on the head in constricting the cap skirt, is taken up in the spring by the compression thereof, which 5 is caused by the extension of the inner tube section and rod assembly, the amount of said extension being indicated by the space 170 existing between the inner end of the rod and the plug 163 at the inner end of the inner tube, as shown in Fig. 7. Likewise, when the crank is on dead center relation with the resilient link and extending theretoward, in causing the operation of the capping head 35, the pressure exerted on the head in causing the constriction of the cap skirt 10 is also taken up in the spring by the compression thereof, which is caused by the contraction of the tube sections an amount equal to the amount the inner tube and the rod are extended, as seen in Fig. 7.

20 The resilient link may be said to be resiliently locked in a neutral length, from which it is capable of extension or contraction by the same stressing action of a single spring. This construction promotes uniformity of caps as applied to the 25 bottles by both heads.

The coupling 137 between the power shaft and its shaft extension, includes a sleeve portion 171 in which the lower end of the shaft extension is slidably received and which has a key 172 received 30 in the keyway 173 in the shaft to rotate same. At the bottom end of the sleeve is a lateral flange 174 connecting with the flange 175 at the top of the gear hub 56, by means of the elongated arcuate slot and bolt connections 176—176—176 there- 35 between. By virtue of the coupling the capping mechanism may be adjusted in time relation with the bottle positioning mechanism, by changing the angularity of the power shaft and its extension, made possible by the slot and bolt connections 40 176.

The connected horizontal upper and lower support members 99 and 74 carrying the cap feeding and capping head mechanisms, are adjusted vertically on the uprights, to accommodate bottles 45 of various height, by means of two vertical screw shafts 177—177, each shaft extending alongside of an upright and rotatably mounted at its top end in a bearing 178 at each end of the strut. Each screw shaft is in threaded connection at its 50 lower end in a threaded boss 179 on each end of the upper support member, and is operably connected, through the intermediation of the bevel gear connections 180, to a horizontal shaft 181 extending over the strut and rotatably mounted 55 in spaced bearings 182 thereon. To facilitate the adjustment of said mechanisms, a hand crank 183 is provided on one end of the shaft 181.

The invention constitutes a further development or improvement on the structure of my 60 Patent No. 1,958,476, of May 15, 1934, relating to Cap applying machines, in which patent certain organizations of the structure herein disclosed, such as the resilient capping head driving means and the cap feeding means, are broadly 65 disclosed and broadly claimed.

Having thus described my invention, I claim:

1. In a container capping machine, two reciprocably mounted capping heads each having means for positioning a cap and being adapted 70 to apply the cap upon the reciprocation thereof, means for reciprocating the heads in alternation so that one head is held stationary during the reciprocation of the other head, and cap feeding means mounted to be movable, being operably connected with the heads and arranged to be

brought into cooperative relation with the cap positioning means of the heads when same are held stationary.

2. In a container capping machine, two reciprocably mounted capping heads each having means for positioning a cap and being adapted to apply the cap upon the reciprocation thereof, means for reciprocating the heads in alternation so that each head is held stationary at an interval of the cycle of operation of the other head, and cap feeding means mounted movable back and forth in a fixed path and operably connected with the heads and arranged whereby it is brought into cooperative relation with each head cap positioning means when same is held stationary.

3. In a container capping machine, two reciprocably mounted capping heads each having means for positioning a cap and being adapted to apply the cap upon the reciprocation thereof, means for reciprocating the heads in alternation so that one head is held from reciprocating at an interval of the cycle of operation of the other head, and means for feeding caps, said heads and feeding means mounted and arranged to have 100 relative movement whereby said means is brought back and forth into cooperative relation with the cap positioning means of the heads when same are held from reciprocating.

4. In a container capping machine, two reciprocably mounted capping heads each having a recess for receiving a cap and being adapted to apply the cap upon the reciprocation thereof, means for reciprocating the heads in alternation so that one head is held from reciprocating at an 105 interval of the cycle of operation of the other head, and a pivotally mounted gravity feed cap magazine having a discharge end and operably connected with the heads and arranged whereby it oscillates so that the discharge end is brought 110 alternately in to cooperative relation with the recesses of the heads when same are held.

5. In a container capping machine, two capping heads mounted reciprocable vertically, a continuously oscillating lever for operating each 120 head, the levers being operably connected to oscillate alternately, releasable locking means for holding each head in raised position, means operative at a certain interval of a cycle of operation of the levers for effecting a positive operable connection between the levers and their respective heads and causing the release of locking means whereby the heads are intermittently reciprocated in alternation.

6. In a container capping machine, two reciprocably mounted capping heads each having means for applying a cap to a container upon pressure engagement therewith when reciprocated, an oscillatably mounted arm operably connected to the heads to reciprocate same alternately upon an oscillation thereof, an operating crank, and resilient linkage connecting the crank with the arm whereby the arm is resiliently oscillated.

7. In a container capping machine, the combination of two reciprocably mounted capping heads each having means for applying a cap to a container upon pressure engagement therewith when reciprocated, a driven element mounted movable back and forth in a given path and operably 145 connected with the heads to alternately reciprocate same upon its said movement, a driving element movable back and forth, and resilient linkage operably connecting said elements, wherein said linkage includes a spring and means 150

whereby motion is transmitted from the driving element to the driven element in both directions of its movement through the stressing of the spring in one manner of operation.

5 8. In a container capping machine, the combination of two reciprocably mounted capping heads each having means for applying a cap to a container upon pressure engagement therewith when reciprocated, a driven element mounted 10 movable back and forth in a given path and operably connected with the heads to alternately reciprocate same upon its said movement, a driving element movable back and forth, and resilient linkage operably connecting said elements, 15 wherein said linkage includes a spring, and means whereby said elements are normally operably connected through the spring under stress and permitting independent movement of either of said elements in either directions of their movement and at any interval of their cycle of operation through increased stressing of the spring in 20 one manner of operation.

9. In combination in a capping machine, capping mechanism, operating mechanism adapted 25 to have intermittent cooperative connection with the capping mechanism, a locking device associated with the capping mechanism normally operative to hold said mechanism inoperative and being controlled by the operating mechanism 30 upon its connection with the capping mechanism for effecting its release in rendering the capping mechanism operative.

10. The structure as defined in claim 9, including means associated with the operating 35 means and the locking device operable upon the release of the device for completing the operable connection between the applying and operating mechanisms.

11. In combination in a capping machine, an 40 operated cap applying element, an operating element adapted to have intermittent cooperative connection with the applying element to operate same, a stop element, a holding element movably associated with the capping element and normally resiliently pressed into operative connection 45 with the stop to hold the applying element normally inoperative, and said holding and operating elements having portions formed to operate during connection of the operating element to the applying element whereby the holding element is released.

12. The structure as defined in claim 11, including portions formed on the operating and holding elements to cooperate upon the release

of the holding element for completing the cooperative connection between the applying and operating elements.

13. In a container capping machine, two capping heads, and means for retaining a supply of caps to be fed mounted movable back and forth between fixed limits, said heads and means arranged whereby at each limit of its movement the means is brought into and out of cooperative relation with a separate head. 80

14. In a container capping machine, two capping heads, and a cap supply magazine mounted movable back and forth between fixed limits, said heads and magazine arranged whereby at each 90 limit of its movement the magazine is brought into and out of cooperative relation with a separate head.

15. In a container capping machine, two capping heads mounted operably at separate fixed locations, and means for retaining a supply of caps to be fed mounted movable back and forth between fixed limits, said means arranged whereby upon its movement it is brought into and out of cooperative relation with a separate head at each 95 limit of its movement.

16. In a container capping machine, two capping heads mounted operably at fixed locations, and a cap supply magazine mounted movable back and forth between fixed limits and arranged whereby at each limit of its movement it is in 100 cap supplying relation with a separate head.

17. In a container capping machine, two capping heads mounted movable in separate fixed paths, and means for retaining a supply of caps to be fed mounted movable back and forth between fixed limits and arranged whereby at each 110 limit of its movement it is in cooperative relation with a separate head.

18. The structure as defined in claim 17, including means for holding the heads stationary 115 when in cooperative relation with said cap retaining means.

19. In a container capping machine, two movably mounted capping heads, each head having means for receiving a cap, means for operating the heads in alternation so that one head is held stationary at an interval of movement of the other head, and means for feeding caps mounted movable back and forth and arranged whereby it is brought alternately into and out of cooperative 120 relation with the cap receiving means of the heads when same are held stationary. 125
